CLAIM

I claim the ornamental design for the glider rocker, as shown and described.

DESCRIPTION

FIG. 1 is a perspective view of a first embodiment of the design of the present invention for a glider rocker;

FIG. 2 is a right side view thereof; a left side view being a mirror image thereof;

FIG. 3 is a front view thereof;

FIG. 4 is a back view thereof;

FIG. 5 is a top view thereof; and

FIGS. 1, 2, 3, 4 and 5 illustrate with phantom lines, cushions which are shown for purposes of environment only.

FIG. 6 illustrates a perspective view of a second embodiment of the design of the present invention incorporating alternate, fluted back posts showing our new design;

FIG. 7 is a right side view thereof; a left side view being a mirror image thereof;

FIG. 8 is a front view thereof;

FIG. 9 is a back view thereof; and,

FIG. 10 is a top view thereof.

FIGS. 6, 7, 8, 9, and 10 illustrate with phantom lines, cushions which are shown for purposes of environment only.
